[57] CLAIM

The ornamental design for an overall side panel, as shown and described.

DESCRIPTION

FIG. 1 is a front perspective view of an overall side panel showing my new design, with the broken line overalls included for purposes of illustration only and forming no part of the claimed design;

FIG. 2 is a front elevational view of the panel;

FIG. 3 is a left side elevational view thereof;

FIG. 4 is a right side elevational view thereof;

FIG. 5 is a bottom plan view thereof;

FIG. 6 is a top plan view thereof; and

FIG. 7 is a rear elevational view thereof.

FIG. 1FIG. 5FIG. 3 FIG. 4FIG. 6FIG. 2
